UNITED STATES PATENT OFFICE.

LOUIS F. BONALY, OF LEAVENWORTH, KANSAS.

SPRINGLESS DOOR LOCK AND LATCH.

1,326,173.

Specification of Letters Patent. Patented Dec. 30, 1919.

Application filed April 17, 1919. Serial No. 290,713.

To all whom it may concern:

Be it known that I, LOUIS F. BONALY, a citizen of the United States, residing at Leavenworth, in the county of Leavenworth 5 and State of Kansas, have invented certain new and useful Improvements in Springless Door Locks and Latches, of which the following is a specification.

This invention relates to springless door locks and latches, and is designed more especially as an improvement in the door lock on which Patent No. 1,164,982 was issued on the twenty-first day of December, 1915. The object of the present invention is to 15 generally improve the construction of said patented lock and the efficiency of its operation and make it more difficult of unlocking operation by any means other than the appropriate key.

20 To this end the invention consists in certain novel and useful features of construction and organization of parts as herein-after described and claimed; and in order that it may be fully understood reference 25 is to be had to the accompanying drawing, in which:

Figure 1, is a side view of a lock embodying my invention with the face plate omitted to disclose the internal construction 30 and arrangement of the parts.

Fig. 2, is a vertical section on the line II—II of Fig. 1.

Fig. 3, is a vertical section on the line III—III of Fig. 1.

35 Fig. 4, is a fragmentary section on the same line as Fig. 3, but looking in the opposite direction.

Fig. 5, is a horizontal section taken on the line V—V of Fig. 1.

40 Fig. 6, is a fragmentary view corresponding to Fig. 1, but showing the tumbler locking catch sectioned and the tumbler advanced to lock the bolt in its advanced position.

45 Fig. 7, is a detail perspective view of a tumbler.

In the said drawing, 1 indicates a rectangular lock casing of conventional form and provided with a key-hole 2, a knob operated shaft 3, and a bolt comprising a latch piece 4 extending slidingly through the outer edge of the casing, and an arm 5, the rear end of the bolt being of yoke form and having outwardly facing shoulders 6. 50

55 The yoke end of the bolt slides on the bot-

tom of the casing and against the under-side of a post 7, which post and a post 8, are adapted to receive the screws by which the removable face plate 9 of the casing, is secured in position. The post 7 may be 60 utilized as a stop for a weight hereinafter referred to, and the post 8, in conjunction with the inner edge of the casing, as a guide for said weight, and said post 8 in conjunction with a post 10 and the outer 65 edge of the casing, constitute means for guiding a weight 11, also adapted for vertical reciprocatory movement. The weight 11 rests upon a rocker lever 12 pivoted at 13 intermediate its ends and bearing at its 70 outer end against the inner side of the bolt arm 5 to hold the latter, under the pressure of the said weight 11, slidingly advanced, and to retract the bolt the knob shaft 3 is provided with a double crank 14 to apply 75 pressure according to the direction the knob is turned, on the opposing bolt shoulder 6, this retraction of the bolt effecting the operation of the rocker lever and the lifting of the weight 11. It will thus be seen that 80 by the construction thus far described, the weight 11 is utilized to maintain the bolt advanced, and that the latter may be retracted not only by operation of one of the knobs but will also retract when the door 85 is closed by engagement of the beveled side of the latch piece 4 with the bolt socket (not shown) adapted for the reception of said latch piece.

A shouldered pivot post 15 within the 90 casing is located vertically above the post 10, and fitting on said post and extending between the upper edge of the casing and the post 10 is a bar 16, the lower end of said bar being flat and fitting squarely 95 against the post 10 so as to be incapable of pivotal operation, the removal plate 9 of the casing guarding against dislocation of said bar.

Pivots suspended from said pivot post 100 15 and fitting snugly between the bar 16 and the back plate of the casing is a tumbler actuated locking arm 17. The bar 16 is provided with a recess 17^a in its rear side, and projecting therein and pivoted to a pin 18 105 carried by said bar is a tumbler-controlling latch 19, the same having a short arm 20 projecting from its free or rear end into a vertical slot 21 in a vertical bar 22 projecting from a plate 23 fastened in any suit- 110

able manner to the inner side of the back wall of the casing and serving to thicken and reinforce the wall around the key-hole, and said latch is provided in its lower edge 5 with a segmental recess 24, and at its upper edge with a horizontal lug 25 underlying and engaged by a horizontal arm 26 projecting from a vertical extension 27 of the weight 28 hereinbefore mentioned but not 10 identified, said weight normally resting on post 7 and fitting snugly between post 8 and one edge of the casing. The body of the weight is shown as extending upward beyond the lower end of the key-hole and 15 consequently is provided with a segmental recess 29 in its upper edge to accommodate the turning of the key employed in connection with the lock, it being understood that when the key is turned, it must by engagement 20 with the recessed edge of the catch 19, pivotally raise the latter and hence lift the weight, and that the latter when unresisted returns the latch to its normal position.

Arranged against the rear side of the latch 25 is a plurality of tumblers 30, pivoted at one end as at 31 to the lower end of swing arm 17 pivotally suspended from the pivot post 15 between the back of the casing and the bar 16, and said tumblers are provided 30 at their opposite ends with arms 33 extending slidingly through the slot 21 in bar 22 and also into a vertical slot 34 in the vertical arm 27 of the weight 28. The arms 33 are provided in their lower edges with pairs 35 of notches 35 and 36 and in the normal position of the tumblers the notches 35 engage the bar 22 at the lower edge of the slot thereof, and thus normally lock the swing arm 17 in vertical position. The 40 tumblers are provided with segmental recesses 37 in their lower edges and with notches 38 opening into said recessed edges, and when the key is turned a notch or ward in the bit of the key receives the recessed 45 edges of the tumblers and raises the same pivotally high enough to disengage notches 35 from the bar 22, and then the ward of the key engages the notches 38, while retaining the tumblers elevated and disengaged 50 from the bar 22, so that continued movement of the key shall move the tumblers to the right and thus swing the swing arm 17 in the same direction until the lower end enters a notch 39 in the upper left 55 hand corner of the weight 11, and as this occurs the tumblers swing down until their notches 36 engage the bar 32 and thus lock the swing arm in the position mentioned and hence the weight 11 in its depressed 60 position. This positioning of the parts mentioned of course prevents pivotal action of the rocker bar 12 and hence locks the bolt advanced.

Reverse operation of the key results in 65 reelevating the catch and then the tumblers

until notches 36 of arms 33 are out of engagement with the bar 22, and then the engagement of the key with the notches 38 moves the tumblers to the left and hence withdraws the locking swing arm 17 to its 70 original position and leaves the weight 11 free to be moved upward, the release of the tumblers and the catch by the key permitting the former to drop down until notches 35 are engaged again with the bar 22 to lock 75 the swing arm 32 in unlocked position, and the weight 28 to drop and force the catch down upon the tumbler to guard against accidental upward movement thereof.

It will be seen that if the ward of the 80 key is too shallow for the depth of recess 37 of the tumbler, or too deep to permit the notched portion of the latter to drop into the ward, it will be impossible to effect movement of the locking arm 32, it being 85 noted that as the tumbler is in duplicate, the key must be formed to operate both simultaneously to effect adjustment of the locking arm. Multiplication of the tumblers of course makes the lock more difficult to pick. 90

From the above description it will be apparent that I have produced a springless door lock and latch which possesses all of the features of advantage pointed out, and while I have illustrated the preferred embodiment of the same I reserve the right to make all changes which fall within the spirit and scope of the appended claims. 95

I claim:

1. In a combined door lock and latch, a 100 casing, a reciprocatory bolt therein, knob actuated means for retracting the bolt, a rocker lever engaging the bolt, a vertically movable weight adapted in its downward movement for operating the rocker lever 105 to advance the bolt, a locking arm movable independently of said weight, and key actuated means for disposing said arm in the path of upward movement of said weight after the latter has assumed its most 110 depressed position, to lock the bolt in its advanced position.

2. In a combined door lock and latch, a 115 casing, a reciprocatory bolt therein, knob actuated means for retracting the bolt, a rocker lever engaging the bolt, a vertically movable weight adapted in its downward movement for operating the rocker lever to advance the bolt, a locking arm movable independently of said weight, key actuated means for disposing said arm in the path of upward movement of said weight after the latter has assumed its most depressed position, to lock the bolt in its advanced position, and means to lock said 120 locking arm in said last named position.

3. In a door lock, a bolt, yielding means for holding the bolt advanced, knob operated means to retract the bolt, a swing arm, a tumbler pivotally connected to the swing 125 130

arm and adapted for actuation by a key to dispose the swing arm in position to lock the said yielding means against unlocking movement and for reverse actuation by such 5 key to return the swing arm to normal position, and means for locking the tumbler in either of its said positions.

4. In a door lock, a bolt, yielding means for holding the bolt advanced, knob operated 10 means to retract the bolt, a swing arm, a tumbler pivotally connected to the swing arm and adapted for actuation by a key to dispose the swing arm in position to lock the said yielding means against unlocking 15 movement and for reverse actuation by such key to return the swing arm to normal position, a slotted bar in the casing, and an arm projecting from the tumbler through said slotted bar and provided in its lower edge 20 with a pair of notches, one for engagement with said bar when the tumbler is advanced,

and the other for engagement with said bar when the tumbler is retracted.

5. In a door lock, a bolt, yielding means for holding the bolt advanced, knob operated 25 means to retract the bolt, a swing arm, a tumbler pivotally connected to the swing arm and adapted for actuation by a key to dispose the swing arm in position to lock the said yielding means against unlocking 30 movement and for reverse actuation by such key to return the swing arm to normal position, a pivoted latch having a lug overlying and engaging the tumbler, a slotted bar receiving the free ends of the tumbler and 35 latch, the former having notches in its lower edge, and a weight engaging the latch for holding the same depressed and the tumbler with either of its notches in engagement with the said bar. 40

In testimony whereof I affix my signature.
LOUIS F. BONALY.
